UNITED STATES PATENT OFFICE.

ISIDOR ROSENBLATT, OF NEW YORK, N. Y.

DESIGN FOR A BODY FOR LANTERNS OR ARTICLES OF SIMILAR NATURE.

Application filed June 3, 1927. Serial No. 22,305. Term of patent 3½ years.

To all whom it may concern:

Be it known that I, ISIDOR ROSENBLATT, a citizen of the United States, and a resident of the city, county, and State of New York, have invented a new, original, and ornamental Design for a Body for Lanterns or Articles of Similar Nature, of which the following is a specification, reference being had to the accompanying drawings, forming a part hereof.

The figure in the drawing shows a perspective view of a body for lanterns or articles of similar nature.

I claim:

The ornamental design for a body for lanterns or articles of similar nature substantially as shown.

ISIDOR ROSENBLATT.
